UNITED STATES PATENT OFFICE.

GEORGE ARTHUR WILLIAM RUSHWORTH, OF WILLINGTON, MANCHESTER, ENGLAND.

SELF-INKING PRINTING-STAMP.

1,345,255.

Specification of Letters Patent. Patented June 29, 1920.

Application filed December 9, 1919. Serial No. 343,634.

To all whom it may concern:

Be it known that I, GEORGE ARTHUR WILLIAM RUSHWORTH, a British subject, residing at Willington, Manchester, England, have 5 invented certain new and useful Improvements in Self-Inking Printing-Stamp, of which the following is a specification.

This invention relates to self-inking printing stamps in which the rubber or other 10 printing surface is carried in a movable frame and held normally against a stationary inking pad by a spring and turned over and away from the inking pad by the depression of the handle for the operation of 15 printing, this type of stamp being known as a turn-over self-inking stamp.

Although indicating means have been employed in other types of printing devices to indicate the position of the imprint, such 20 means have not hitherto been applied to turn-over self inking stamps above referred to.

The invention consists in a printing stamp having a transparent indicator or a frame 25 carrying a transparent indicator pivoted to the frame of the stamp and providing means for causing the indicator or frame carrying the indicator to be rotated about its pivots out of the path of the printing surface when 30 the latter is depressed.

The invention will be fully described with reference to the accompanying drawings which show it in various forms.

Figure 1 is a perspective view of a self-inking stamp showing the invention applied 35 in the form of a separate attachment, the stamp being in the up position.

Fig. 2 is a perspective view of same form of the invention with the stamp in the down 40 or printing position.

Fig. 3 is a section of same form of the invention with the stamp in the up position.

Fig. 4 is a section of same form of the invention with the stamp in the down or printing 45 position.

Fig. 5 is a perspective view of a modified form of the attachment.

Fig. 6 is a perspective view of a further modification of the attachment.

Fig. 7 is a perspective view of frame of 50 stamp showing guide for the transparent index plate.

Fig. 8 is a perspective view of the attachment E shown in position in Figs. 1-4.

Figs. 9 and 10 are perspective views of a 55

modified form of the invention showing the stamp in the up and down position respectively.

Fig. 11 is a perspective view of modification shown in Figs. 9 and 10 detached. 60

The frame A, inking pad B, reciprocating frame C carrying the type pad D, and the means for swiveling over the type pad, are all of ordinary or known construction. The inking pad B is either affixed to the frame A 65 or free to pull or push out therefrom to be renewed or re-inked such as is known as a "tip-up" (removable) pad.

In the form of the invention shown in Figs. 1 to 4, and Fig. 8, a swinging frame E 70 is affixed to the top of the frame A by the member e about which the swinging frame can pivot at the edge of the frame A. The frame E is provided with two upwardly extending arms or levers e' adapted to be engaged by the underside of the reciprocating frame C when the latter is depressed. To the lower end of the frame E is attached a transparent plate F. Guides or grooves f 75 are formed at the bottom of the frame A for the transparent plate F to slide in. The transparent plate F is lettered or otherwise marked to indicate the position the print or impress from the stamp pad D will take.

The normal position of the pad is that 85 shown in Figs. 1 and 3 with the transparent plate F in position below the printing stamp D and the arms e' of the frame E projecting upward. When the reciprocating frame C is depressed, the underside engages the arms e' 90 and depresses them, causing the frame E to swing outward and move the transparent plate F out of the path of the descending printing stamp D, so that the latter can leave its impression or print on the surface 95 of paper or material placed beneath the stamp. The removal of the pressure from the handle C' of the reciprocating frame C, allows the latter to return to its normal position by the action of the usual spring within 100 the handle C', and the pressure being at the same time removed from the arms e' the frame E swings back by reason of its weight to its normal position with the transparent plate F underneath the printing stamp D 105

The transparent plate F may be made of celluloid, gelatin, mica, tracing cloth, fine muslin, or other suitable material and has printed upon it an imprint from the printing stamp D (or other lines or index marks) 110

which will indicate to the user the exact position that the impression or print will take.

- Instead of being formed as described with reference to Figs. 1-4 and Fig. 8, the swinging frame E may be formed as shown in Fig. 5, or Fig. 6. In Fig. 5 the frame E is pivoted at e^2 to the sides a of the frame A the attachment member e being unnecessary in this case. In Fig. 6 the frame E is provided with a cylindrical portion e^3 to receive a pin carried on the edge of the top of the frame A by projections a' such as shown in Fig. 7. The frame shown in Fig. 7, is provided with guide pieces f for the transparent plate formed in one piece with the frame, extra guide pieces f' being pressed out of the frame, or otherwise to form a complete guide if desired.
20. The swinging frame E shown in Fig. 6, is only provided with one upwardly extending member e' with a slot e^4 for the stem c of the handle of the reciprocating frame C, and a similar construction may if desired be applied to the frames shown in Figs. 1-4 and Fig. 5.

In the form of the invention shown in Figs. 9, 10 and 11, the transparent plate F is affixed at one edge to a strip a' of metal or other material pivoted on the transverse bar a^2 of the frame A. One end a^3 of the strip a' is bent at right angles to form an upwardly extending lever—or a separate lever is affixed to the end of the strip a' and the lever a^3 is slotted to receive a pin a^4 carried on the free end of a lever a^5 the other end of which is pivoted on the bar a^6 about which the printing stamp D oscillates, or to any other convenient point on the reciprocating frame C. When the stamp is depressed from the position shown in Fig. 9, to the position shown in Fig. 10, the downward movement of the end of the lever a^5 pushes the slotted lever a^3 outward and

causes the transparent plate to rotate about 45 the bar a^2 into the position shown in Fig. 10 out of the path of the descending stamp.

Instead of being made as part of the stamp the transparent plate F may be formed as shown in Fig. 11 to be attached to existing stamps. The plate F is affixed to a bar a' provided with holes at the ends to fit over pins on the sides a of the stamp.

What I claim as my invention and desire to protect by Letters Patent is:—

1. In a turn-over self-inking printing stamp the combination with a transparent indicating plate of means operated by the depression of the printing surface to cause the said indicator to rotate about the frame 60 of the stamp out of the path of the printing surface.

2. In a turn-over self-inking printing stamp the combination with a transparent indicating plate of a frame carrying the indicator stamp and means operated by the depression of the printing surface to rotate about the frame of the stamp out of the path of the printing surface.

3. In a turn-over self-inking printing stamp the combination with a transparent indicating plate of a member carrying the indicating stamp, a pivot on the frame of the stamp for the said member, a slotted lever affixed to one end of said member, a connecting lever affixed to the underside of the printing surface, a pin in said lever engaging the slot in the slotted lever to cause the rotation of the transparent plate out of the path of the printing surface as the latter descends.

In testimony whereof I have hereunto set my hand in presence of two subscribing witnesses.

GEORGE ARTHUR WILLIAM RUSHWORTH,
Witnesses:

J. OWDEN O'BRIEN,
GEO. H. O'BRIEN.
